CLAIM

I claim the ornamental design for a blank firing adapter, substantially as shown and described.

DESCRIPTION

FIG. 1 is a top disassembled plan view of a blank firing adapter in accordance with an embodiment of a present design;

FIG. 2 is a front elevation view thereof;

FIG. 3 is a right side disassembled elevation view thereof;

FIG. 4 is a bottom disassembled plan view thereof;

FIG. 5 is a rear elevation view thereof;

FIG. 6 is a disassembled perspective view thereof;

FIG. 7 is an assembled perspective view thereof in an unclaimed environment;

FIG. 8 is a partially assembled top plan view thereof in an unclaimed environment; and,

FIG. 9 is an assembled perspective view thereof in an unclaimed environment.

Broken lines are used to illustrate unclaimed environmental structure of a flash hider and form no party of the claimed design.
